To all whom it may concern:

Be it known that I, ALFRED A. HALLOCK, a citizen of the United States, residing at Farmingdale, in the county of Nassau and State of New York, have invented and produced a new and original Design for a Coffin-Handling Hook, of which the following is a specification, reference being had to the accompanying drawings, forming part thereof.

The invention consists in an arch c', having depending vertical arms c connected to its respective ends, each of these arms c being connected to a horizontal arm a, having an upturned tapered extremity b, said arms a projecting toward the same side of the arch and lying approximately parallel with each other and at right angles to the vertical arms c. Connected to the center of the arch and extending upward and outward toward the side opposite the arms a is a vertical post d, to the upper end of which is connected a horizontal handle e, which lies in a vertical plane outside of the arch and at right angles to the vertical planes of the arms a.

Having described my invention, I claim—

The design for a coffin-handling hook, substantially as herein shown and described. 30
